Inventor:
George Frederick French

By his Attorney: Walter Gurn

UNITED STATES PATENT OFFICE

GEORGE FREDERICK FRENCH, OF MANCHESTER, ENGLAND

CURTAIN RAIL SUPPORT

Application filed May 7, 1929, Serial No. 361,208, and in Great Britain October 26, 1927.

This invention refers to brackets for supporting holeless flat web section curtain rails.

In the known brackets, the rail is supported by two jaws and a screw, one of the jaws being separable from the other jaw to admit the top edge of the rail, and being then movable by the screw towards the other jaw to grip the rail.

10 One of the objects of this invention is to dispense with the movable jaw and thereby simplify and cheapen the bracket.

A still further object is to provide a one-jaw bracket which allows of the rail being secured to the bracket, and to the window casement by a single screw.

20 A still further object is to provide a one-jaw bracket which in one form allows of the rail being secured to it independently of fixing it (the bracket) to the window casement or other support, and in another form allows of the two operations being effected by a single screw.

Examples of brackets made according to 25 the invention are shown upon the accompanying drawings, wherein:

Fig. 1 is a front perspective view of a bracket adapted to be secured to the window casement or other support by a single 30 long screw, the screw not being shown.

Fig. 2 is a rear perspective view of the same bracket.

Fig. 3 is a side sectional elevation of the bracket shown in Figs. 1 and 2, and also 35 shows a long screw for fixing same.

Fig. 4 is a longitudinal section of a modification of Fig. 1.

Referring to Figs. 1, 2, and 3, the body part *a* of the bracket therein shown is made 40 of sheet metal cut and folded to produce three flat sides, and also to produce a transverse flap and lugs *b*, *b*, at one end and a turned down flap *c* at the other end. In the front edges of the vertical sides of the body

45 part are recesses *d* collectively forming the single jaw aforesaid. The flap *c* is slightly shorter in length than the depth of the sides of the body part of the bracket and its bottom edge lies on a level with the top sides

50 of the recesses *d*. In the flap *c* is a hole or

opening *e* which may be a complete hole with only a thin portion of metal between it and the bottom edge of the flap, see Fig. 6, or as shown, it may extend through such edge, see Fig. 1. Passing through such hole 55 or opening is the stem of a long screw *f*, see Fig. 3, the screwed part passing out through a hole *g* in the rear of the bracket and into the window casement when requiring to fix the bracket thereto. That part 60 of each front vertical edge of the body part of the bracket below the recess *d* stands back from the plane of the upper part to an extent equal to the thickness of the web of the curtain rail to be supported, see 65 Fig. 3.

At the rear of the bracket are small spurs *h* formed out of the metal at the time of making the hole for the screw, and on the bracket being first applied to the window 70 casement, the spurs project into the wood-work under a slight pressure of the hand, and temporarily attach the bracket to the casement.

In proceeding to fix the bracket to the 75 casement, the screw *f* is first passed through the bracket and screwed into the casement a sufficient distance to support the bracket. The top edge of the curtain rail is then passed between the front end of the bracket 80 and the screw head, the flange of the rail entering the recesses *d*, and thus supporting the rail, and the screw then being tightened up until its head part presses firmly against the plain side of the rail, when the bracket 85 is firmly fixed to the casement and the rail firmly fixed to the bracket. Simultaneously with the tightening of the screw, the spurs *h* are driven home into the casement, so that the bracket has no tendency to rotate 90 with the screw, and so also that, on afterwards slackening the screw to release the rail the spurs still hold the bracket to the casement.

As shown in Fig. 4, spurs may be formed 95 upon the rear face of the flap *c*, to form a guide for the screw when first inserting same through the hole in the flap *c*.

What I claim is:—

1. A bracket for supporting a flat web 100

- section curtain rail, composed of sheet metal cut and folded to produce an inverted channel-shaped body part with a flap at each end and each flap having a hole for a screw to pass through in fixing the bracket to a window casement, and the flap at the rear of the bracket having rearwardly projecting spurs immediately surrounding the hole, the front vertical edges of the said body part, and a screw passing over the rail and through the flaps and into the casement to which the bracket requires to be fixed and on said screw being tightened up firmly holding by its head part the flange at the top edge of the rail in engagement with the recesses in the bracket and simultaneously driving all the spurs at the rear end of the bracket into the casement, as set forth. 70
- 5 In testimony whereof I have signed my name to this specification. 75
- GEO. F. FRENCH.
- 10 part of the bracket having a recess at a point immediately below the lower edge of the flap and that part of each front vertical edge below the recess being set back out of the plane of the upper part of such edge, 80
- 15 and a long screw passing through the holes in the flaps and by its head part when tightened up firmly holding the flange of the top edge of a curtain rail in engagement with the recess and simultaneously driving all the spurs at the rear end of the bracket into the casement, as set forth. 85
- 20 2. In a bracket for supporting a flat web section curtain rail, a body part composed of sheet metal cut and folded to form an inverted channel-shaped body part and to produce turned down end flaps, the flap at one end having an opening which breaks through the lower edge of the flap, and the flap at the other end having a circular hole and rearwardly projecting spurs immediately surrounding the hole, the vertical edges at the opposite and front end of the bracket having recesses for engagement with a flange at the top edge of the rail to be supported, that part of each front vertical edge being set back out of the plane of the upper part, and a screw passing over the rail and through the flaps and into the casement to which the bracket requires to be fixed and on said screw being tightened up firmly holding by its head part the flange at the top edge of the rail in engagement with the recesses in the bracket and simultaneously driving all the spurs at the rear end of the bracket into the casement, as set forth. 90
- 25 30 35 40 45 50 55 60 65 70 75 80 85 90 95 100 105 110 115 120 125 130
2. In a bracket for supporting a flat web section curtain rail, a body part composed of sheet metal cut and folded to form an inverted channel-shaped body part and to produce turned down end flaps, the flap at one end having an opening which breaks through the lower edge of the flap and the edge of which projects into the body part of the bracket in the form of spurs, while the flap at the other end of the bracket has a circular hole and rearwardly projecting spurs immediately surrounding the hole, said rear flap being wider than the body part of the bracket and having a further hole near each end, the vertical edges at the opposite and front end of the bracket having recesses for engagement with a flange at the top edge of the rail to be supported, and that part of each front vertical edge being set back out of the plane of the upper
